UNITED STATES PATENT OFFICE.

ERWIN C. COOPER, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed October 9, 1925. Serial No. 61,575.

This invention relates to internal combustion engines and particularly to pump mechanism therefor.

One of the objects of the invention is to provide an oil pump for internal combustion engines in which the air may be quickly exhausted from the chamber from which the pump draws its oil.

Another object of the invention is to provide means for quickly freeing the oil system of air.

Another object of the invention is to provide an air vent to the intake side of a pump for quickly exhausting the air from the chamber from which the pump draws its supply.

Other objects of the invention will appear from the following description taken in connection with the drawings, which form a part of this specification and in which:

20 The one figure of the drawings is a sectional view through an engine crank case and a pump therein made in accordance with this invention.

Referring to the drawing, 10 represents the 25 crank case of an internal combustion or other engine and 11 is a cover which, with the opening 12 in the crank case, forms a depression 13 in the lower part of the crank case into which the oil collects. 14 is a pump preferably of the gear type, one of the gears 15 being shown in elevation in the drawing. This pump is supported by its flange 16 on a part 17 of the crank case, and a vertical shaft 18 is connected to one of the gears of the 30 pump and forms the driving means therefor.

The intake side of the pump is indicated at 19 and the outlet or pressure side is shown at 20, and the pipe 21 connects the pressure side of the pump to the various bearings of 40 the engine for supplying lubricant thereto under pressure.

The section through the pump is taken to show the various ports and chambers of the pump and not to illustrate the exact construction which provides for insertion and removal of the gears, which is immaterial as far as this invention is concerned. As a matter of fact, one of the gears of the pump is removed upwardly and one is removed downwardly 45 through suitable openings provided therefor.

Means forming an intake from the lower part of the crank case and preferably beneath the pump is shown in the form of a member 22 which is connected to the lower 50 part of the pump and which has a guard 23,

preferably of cylindrical form, connected to it. This guard extends down into the recess 13 in order to insure that the pump will draw oil only from the extreme lower part of the 60 crank case. A screen 24 is mounted upon the member 22 just inside of the guard 23, this screen being of cup form and preferably removable through the opening 12 when the cover 11 is taken off.

The pump 14 is provided with intake conduit means in the form of a pipe 25 which is formed in the member 22 and extends from the intake 19 of the pump to the lower part of the chamber 26 formed by the guard 23. Thus the pump draws its oil from the lower 70 part of the chamber 26.

The pump is also provided with an overflow from its pressure side 20. A port 27 is controlled by a ball valve 28 held to its seat by a spring 29 which is adjustable by a nut 30 and a lock nut 31. An opening 32 permits the overflow oil from the port 27 to pass back into the chamber 26. In this manner the maximum pressure in the pipe line 21 is controlled by this overflow valve.

In the pump construction and arrangement described above, it has been found that under some conditions air collects in the chamber 26 when the engine is stopped and it takes some time to get the air out due to 85 the location of the intake 25 in the lower part of the chamber. This presence of air in the system causes the pump to act noisily which is very objectionable in the use of the engine in a motor vehicle. For the purpose of 90 quickly freeing the chamber of this entrapped air and thus at once quieting the oil system, a vent is provided in the form of a relatively small conduit 33 extending from the upper part of the chamber 26 to the intake side 19 of the pump. As shown, this conduit 33 is drilled through the upper wall of the member 22 and through the casing parts of the pump 14. It preferably extends to the upper part of the intake 19 so that the 100 air is at once passed through the pump and into the pipe line 21 and expelled through the bearings of the engine. At the same time this does not in any way interfere with the 105 operation of the pump after the air has been expelled.

While I have herein described in some detail a specific embodiment of my invention, which I deem to be new and advantageous and may specifically claim, I do not desire it 110

to be understood that my invention is limited to the exact details of the construction, as it will be apparent that changes may be made therein without departing from the spirit or scope of my invention.

Having thus described my invention, what I claim and desire to secure by Letters Patent is:

1. In an internal combustion engine, the combination with the crank case, of an oil pump mounted in the crank case and having a downwardly extending guard forming a chamber beneath the pump, the intake of the pump being near the lower part of said chamber, and means forming a relatively small passage from the upper part of said chamber to the intake side of the pump.

2. In an internal combustion engine, the combination with the crank case, of an oil pump mounted in the crank case and having a downwardly extending guard forming a chamber beneath the pump, the intake of the pump being near the lower part of said chamber, and vent means from the upper part of said chamber to the intake side of said pump.

3. In a pump mechanism, the combination of a pump and a supply chamber therefor normally closed at the upper end thereof, an intake pipe for the pump extending to the lower part of said chamber, and means forming a relatively small passage from the up-

per part of said chamber to the intake side of said pump.

4. In a pump mechanism, the combination of a pump, a supply chamber therefor normally closed at its upper end, and normally open intake means for said pump from both the upper and the lower ends of said chamber.

5. In an internal combustion engine, the combination with the crank case having a depression therein, of a pump mounted in said crank case and having a guard extending into said depression and forming a chamber beneath the pump, intake conduit means connecting the intake side of said pump with the lower part of said chamber, valve overflow means from the pressure side of said pump to said chamber, and vent means from the upper part of said chamber to the intake side of said pump.

6. In an internal combustion engine, the combination with the crank case, of an oil pump mounted therein, means forming a chamber open at the bottom whereby oil can enter the chamber from the lower part of the crank case, intake conduit means from the intake side of said pump extending into the lower part of said chamber, and vent means from the upper part of said chamber to the intake side of said pump.

In testimony whereof I affix my signature:
ERWIN C. COOPER.
